UNITED STATES PATENT OFFICE.

JOSEPH O. W. LAVALLEE, OF MONTREAL, QUEBEC, CANADA, ASSIGNEE TO CARON BROTHERS, OF MONTREAL, QUEBEC, CANADA.

INTERNAL-COMBUSTION ENGINE.

1,377,356.

Specification of Letters Patent. Patented May 10, 1921.

Application filed March 11, 1920. Serial No. 365,066.

To all whom it may concern:

Be it known that I, JOSEPH OSCOR WILFRED LAVALLEE, a subject of the King of Great Britain and Ireland, residing at the 5 city of Montreal, Dominion of Canada, have invented certain new and useful Improvements in Internal-Combustion Engines, of which the following is a specification.

10 This invention relates to improvements in internal combustion engines of the two stroke cycle type and more especially to double acting internal combustion engines in which the preliminary compression of the 15 fuel mixture takes place within the piston.

The object of this invention is to provide an engine of the above type, of simple and compact construction in which an explosive impulse is given alternately at each end of 20 the cylinder to every revolution of the crank shaft, and a charge of fuel mixture is taken into one end of the piston and is compressed in time to pass into the adjacent end of the cylinder at the end of each stroke.

25 A further object of this invention is to provide a means of adjusting the pressure of the preliminary compression and of relieving the load of the preliminary compression.

30 A further object of this invention is to provide an engine of the above type in which stuffing boxes are not required in the cylinder or piston, and in which there are no small moving parts within the cylinder 35 which are liable to require adjustment or replacement.

The drawings hereto annexed will illustrate one form of an engine in accordance with my invention.

40 In Figure 1 a vertical section at right angles to the crank shaft is shown.

Fig. 2 shows a vertical section through the axis of the crank shaft.

The double ended cylinder 1 is water jacked 45 et at both ends.

It is preferably constructed in three separable parts, the two end portions being secured to the central portion by means of suitable studs 27.

50 Within this cylinder 1 the double ended piston 2 reciprocates. The bearing 20 cast with the piston contains the wrist pin 4 to the ends of which are secured the connecting

rods 15 outside the cylinder 1, slots 21 being provided in the walls of the cylinder 1. 55

The connecting rods 15 are preferably cast integral with the bearing sleeve 151 in which the crank pin rotates.

Within the piston 2 and secured to the cylinder 1 by the pins 6 is the double ended 60 central member 3. The walls of this central member 3 are slotted at 5 to allow the bearing 20 of the piston 2 to reciprocate. This slotted portion is inclosed as shown in Fig. 1, by the diaphragms 24, which provide cup shaped ends to the central member 3. The walls of this central member cover the slots 14 during the reciprocation of the pinion 2 as shown in Fig. 1.

Spark plugs 7 enter each end of the cylinder 1. Exhaust ports 8 open through the cylinder wall adapted to permit the burnt gases to pass out of the cylinder when the piston has completed its stroke. 70

The by-passes 10 in the cylinder walls also 75 open when the piston is in this position.

Suitable baffles 12 on the ends of the piston surround the area where the by-pass opens.

Inlet ports 9 in the cylinder walls shown 80 adjacent to the exhaust ports 8, are connected with the carburetor and fuel feed in the usual manner.

The piston is provided with inlet ports 13 which register with the inlet ports of the 85 cylinder at the end of each stroke as appears in the lower half of Fig. 1 thereby feeding the interior of the piston end and cup portion of the central member 3 with the fuel mixture when that area is at its 90 greatest extent.

The outlet port 11 in the piston wall meets the by-pass 10 toward the end of the stroke whereby the charge of fuel mixture now compressed within the end of the piston passes through the by-pass into the cylinder end which it fills as the exhaust clears the cylinder of the burnt gases. 95

In addition to the by-pass 10 there may be provided a port 25 leading to a tank 26, 100 the object of which will be set forth hereinafter.

Suitable piston rings or packing 22 are provided near the ends of the piston walls and the like are provided at 23 near the 105 ends of the central member 3.

The crank shaft 17 is journaled in bearings 18 supported by the frames 19. The cranks 16 in the unit as shown are cast with compensating lugs as shown in Fig. 2.

5 The crank pin connecting the cranks 16 rotates within the sleeve 151 connecting the connecting rods 15.

By means of this construction great 10 rigidity and strength are provided with simple compact and light members.

The function of the tank 26 is twofold.

In the first place when the port 11 reaches the by-pass 10 the compressed mixture will 15 fill the tank 26 thereby reducing the pressure within the piston and preventing the cushioning effect toward the end of the piston stroke. By using tanks of various capacities the best feed pressure for obtaining 20 high efficiency can readily be discovered for any size engine.

In the second place with a port 28 in the piston opening into the by-pass 10 opposite the intake port 13, an increased quantity of 25 fuel mixture can be taken into the engine at each stroke.

In describing the operation of this invention and starting from the position shown in Figs. 1 and 2,

The piston is at the lowest limit of its 30 travel and the crank is at its dead center. The lower end of the cylinder is charged with fuel mixture under secondary compression and is ready for ignition from the spark plug.

35 As the port 13 in this end of the piston registers with the lower inlet port 9 a fresh charge of the mixture enters the piston filling the area between the diaphragm 24 and the end of the piston with the mixture.

40 The upper end of the piston is shown as uncovering the exhaust port 8 and the by-pass 10 in which portion the exhaust gases are vacating the cylinder and the mixture under preliminary pressure takes their 45 place, passing from within the upper end of the piston through the port 11 which now registers with the by-pass 10.

After ignition of the lower charge the piston begins to ascend, closing the upper 50 exhaust port 8 and also the upper by-pass and the lower fuel feed port 13.

Proceeding to ascend the charge in the upper end of the cylinder is gradually compressed as is also the fresh charge in the 55 lower end of the piston while the residue of the mixture in the upper end of the piston is expanded and forms a partial vacuum.

When the piston reaches the upper limit 60 of its stroke the position is the reverse of that shown in Figs. 1 and 2. The upper end of the cylinder is now charged with fuel mixture under high compression and the partial vacuum in the upper end of the piston draws in a fresh charge when its inlet 65 port registers with the upper feed port.

The charge in the lower end of the piston now under complete preliminary compression passes through the by-pass and enters the lower end of the cylinder as the spent gases pass out of the lower exhaust port. 70

It will be seen therefore that while the crank shaft is completing one revolution two charges have been taken in to the piston and compressed primarily two charges have been further compressed and exploded 75 and two impulses given to the crank shaft through the connecting rods.

What I claim, is—

1. In an internal combustion engine of the two cycle type, a double ended piston 80 journaled to connecting rods outside the cylinder, and a central cylindrical stationary member within the piston, secured to the cylinder walls by retaining pins through slots in the piston walls, adapted to form 85 compression chambers as described.

2. In an engine of the type specified a central cylindrical stationary member within the piston secured to the cylinder walls and having an inclosed slot therethrough in 90 which the wrist pin of the piston reciprocates.

3. In an engine of the type specified, the combination of a cylinder, a double ended piston therein, with slotted walls, a central 95 stationary member secured to the cylinder by retaining pins which pass through the slots in the piston, a transverse slot through the stationary member, in which a wrist pin journaled in the piston is adapted to reciprocate.

4. In an engine of the type specified, the combination of a double ended cylinder with slotted walls, a double ended piston with slotted walls and having a central 105 transverse bearing, a central stationary member secured to the cylinder walls with an inclosed transverse slot therein, and a wrist pin journaled in the said transverse bearing adapted to reciprocate in the said 110 transverse slot.

5. In an engine of the type specified the combination of a double ended cylinder with slotted walls, a double ended piston therein with slotted walls and a central 115 bearing sleeve, a wrist pin journaled in said sleeve and reciprocating in slots of cylinder walls, connecting rods secured to the ends of the wrist pin outside the cylinder walls and journaled to the crank of a crank shaft, a central cylindrical stationary member, having cup shaped ends, secured to the cylinder walls by retaining pins which pass through the slots in the piston walls and an inclosed slot through said stationary 120 member adapted to permit said sleeve and wrist pin to reciprocate therein.

6. In an engine of the type specified the combination of a double ended cylinder with central longitudinal slots in its walls 130

which have also suitable inlet and exhaust ports, a double ended piston therein having a central transverse bearing sleeve and central longitudinal slots in its walls, suitable 5 inlet and outlet ports in piston walls, a wrist pin journaled in said sleeve and reciprocating in the slots of the cylinder walls, connecting rods secured to the end of the said wrist pin outside the cylinder walls 10 and journaled to the crank of a crank shaft by means of a connecting sleeve, a central cylindrical stationary cylindrical member having diaphragms forming cup shaped ends, and slotted sides between the dia- 15 phragms, the walls adapted to receive retaining pins, which pins are secured to the cylinder walls and pass through slots in piston walls.

7. In an engine of the type specified the 20 combination of a central cylindrical stationary member having an inclosed transverse slot therein, with a double ended piston thereabout having a transverse sleeve central thereto and adapted to reciprocate in 25 said slot, which sleeve forms the bearing of a wrist pin and connecting rods secured to the wrist pin and journaled to the crank of the crank shaft.

8. In an engine of the type specified, a 30 by-pass in the cylinder wall registering with a port in the piston wall, a storage tank adjacent to the by-pass with an opening therefrom adapted to receive the fuel mixture compressed within the piston and to supply 35 it to the cylinder.

9. In an internal combustion engine a 40 double ended cylinder with slotted walls, a double ended piston, a wrist pin journaled in piston, the ends of which pin project through cylinder slots, and connecting rods connected by an integral crank sleeve, secured to the ends of the wrist pin, in combination with a central cylindrical station-

ary member within the piston and secured to the cylinder.

10. In an internal combustion engine a cylinder having heads at opposite ends forming combustion chambers, a hollow piston having heads at opposite ends forming compression chambers, a diametrical wrist 50 pin secured to connecting rods outside the cylinder, journaled in the piston and projecting through slots in the cylinder walls, and a central cylindrical stationary member secured to the cylinder by retaining pins 55 which pass through slots in the piston walls, and having an inclosed slot in which the wrist pin reciprocates.

11. In an engine of the type specified, a central cylindrical stationary member inside the piston, secured to the cylinder walls, having an inclosed transverse slot therein and cup shaped ends as described.

12. In an engine of the type specified, a central cylindrical stationary member se- 65 cured within the piston to the cylinder walls through slots in the piston walls, adapted to cover such slots during the reciprocation of the piston.

13. In an engine of the class specified, a 70 central cylindrical stationary member having cup shaped ends and an inclosed transverse slot in which the wrist pin and sleeve of piston reciprocate, secured to the cylinder by retaining pins through slots in the 75 piston walls and adapted to cover such slots during the reciprocation of the piston.

14. In an engine of the type specified, a double ended piston and a central stationary member therein, having an inclosed 80 transverse slot and cup shaped ends adapted to form compression chambers with the ends of the piston.

In witness whereof, I have signed this specification.

J. O. W. LAVALLEE.
